(57) **CLAIM**

The ornamental design for an LED package, as shown and described herein.

DESCRIPTION

FIG. 1 is a top, front, left side perspective view of an LED package according to the present invention.

FIG. 2 is a front elevation view of the LED shown in FIG. 1, the rear elevation view being a mirror image.

FIG. 3 is a left side elevation view of the LED package shown in FIG. 1, the right side elevation view being a mirror image.

FIG. 4 is a top plan view of the LED package shown in FIG. 1; and,

FIG. 5 is a bottom plan view of the LED package shown in FIG. 1.

Broken lines in the figures are for illustrative purposes only and form no part of the claimed design.
